COLLAR CLASP

Arthur W. Crain, Providence, R. I.

Application April 16, 1936, Serial No. 74,764
Renewed June 3, 1937

10 Claims. (Cl. 24—81)

My invention relates generally to a collar clasp, and particularly to a collar clasp combining collar tab and necktie holding characteristics, and an important object of my invention is to provide 5 a practical arrangement of this character which is very easily applied and removed, and which positively holds the collar tabs in the desired orderly condition and at the same time holds the knot portion of the tie properly between the collar tabs.

Another important object of my invention is to provide a combination collar clasp of the character indicated above which while improving the assembled appearance of collar and tie, tends to 15 eliminate the undue tight tieing of the tie usually required to ensure the knot's staying properly in place, and which produces undue wear on the collar and tie and also discomfort to the wearer.

Another important object of my invention is to provide a mechanically efficient arrangement of the character indicated above which can be manufactured at a comparatively low cost in various ornamental motifs, whereby a practical article 20 of jewelry is provided.

Other important objects of my invention will be apparent from a reading of the following description in connection with the drawing, wherein for purposes of illustration I have shown a 25 preferred embodiment of my invention.

In the drawing:

Figure 1 is a front elevational view of the collar portion of a shirt having a collar equipped with tabs and showing a four-in-hand necktie tied 30 thereon, and illustrating the application of the device of the invention to the collar tabs and to the knot portion of the necktie.

Figure 2 is a front elevational view of the embodiment.

Figure 3 is a plan view of the embodiment.

Figure 4 is a view similar to Figure 3 but showing the embodiment in open position instead of the closed position shown in Figure 3.

Figure 5 is a horizontal sectional view taken 45 through the embodiment showing operative elements thereof in open positions.

Referring in detail to the drawing, the numeral 5 generally designates the device of the invention which is shown in Figure 1 applied to 50 the collar 6 having the respective collar tabs 7 and 8 and to the knot portion 9 of the tie 10.

The device comprises the U-shaped frame 11 which is U-shaped also in transverse cross section to provide at opposite ends the laterally extending pairs of arms 12. Between each pair

of arms is mounted a pivot 13 on which is swingable one of the sections 14 and 15 of the tie clasp which is generally designated 16.

Each of the sections 14, 15 comprises a triangular portion 17 and the narrow curved arm 18 which arm, as indicated in Figure 2 is curved also in a plane which is at right angles to the plane in which the arm curves as shown in Figure 5. The arms are oppositely curved both horizontally and vertically so as to overlap in the manner indicated in Figures 2 and 3 when closed, the tips 19 of the arms being beveled to cause the arms to frictionally slide together into frictional closed engagement in the positions indicated in Figures 2 and 3.

The triangular portion 17 of the sections 14 and 15 has the pivot 13 located near the apex thereof and the main portion is curvilinearly cut away as indicated by the numeral 20 to provide the two rounded tips 21 and 22. When the sections are 20 swung from the open position illustrated in Figures 4 and 5 to the closed position shown in Figure 3, the tip 22 engages the corresponding spring member 23 so that upon flexing the member 23 out of the way the portion 20 of the section 25 comes into engagement with the curved portion of the member 23 so as to be securely locked in the closed position, while at the same time point 21 upon engaging with the spring member 23 acts 30 as a stop or detent which holds the arm 18 securely in the closed position as shown in Figure 3.

The members 23 are pivoted on the frame between the sides thereof as indicated by the numerals 24 to swing toward and away from stationary spring arms 25 which extend from opposite ends of the web of the frame 11. As clearly shown in Figure 2 the arms 23 and 25 extend upwardly from the horizontal, the horizontal plane 35 passing through the frame 11.

As indicated in Figures 3 and 4 the stationary 40 arms 25 are backwardly bowed and have at their outer extremities backwardly angulated tips 26 which are arranged to engage the back side of the collar tabs 7 and 8, respectively; while the swingable spring arms 23 are comparatively straight so 45 as to be spaced from the bowed portion of the arms 25 and have at their outer ends angulated tips 27 which are arranged to register with and engage the tips 26 for engaging the outside of the collar tabs in opposition to the tips 26, so as to 50 clamp the device on the collar tabs.

From the foregoing it will be evident that with the sections 14 and 15 disposed behind the knot portion 9 of the necktie and the stationary arms 25 engaged with the back side of the tabs, and 55

with the swingable arms 23 located in front but not engaging the collar tabs, the respective arms may be made to forcibly engage opposite sides of the collar tabs, and the sections 14 and 15 to surround and confine the knot portion of the tie, simply by urging the sections 14 and 15 together into the overlapping position shown in Figure 3, by manipulating the same with the fingers. The device may be removed from the collar and from the tie simply by separating the sections 14 and 15 by pulling them apart with the fingers.

It is obvious that the swingable arms 23 may have their front sides ornamented as well as being cut in suitable ornamental outline, and that the sections 14 and 15 may be similarly treated, with good effect, in accordance with accepted design principles.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. A combination collar clasp of the character described, said collar clasp comprising a frame, collar tab engaging means on said frame, said means comprising a relatively stationary arm and a movable member pivoted on said frame for swinging toward and away from said stationary arm, tie clasping means on said frame, said tie clasping means including a movable element arranged to be engaged with said movable member for holding said movable member in closed position, said movable element being operable to release said movable member into open position.
2. A combination collar clasp of the character described, said collar clasp comprising a frame, collar tab engaging means on said frame including a stationary member and a member movable relative to said frame and said stationary member, tie clasping means on said frame, and operating connection means between the movable member of said collar tab engaging means and said tie clasping means, said operating connection means effecting movement of said movable member to open and closed positions when a part of said tie clasping means is manipulated to open and closed positions, respectively, said tie clasp means comprising an arm pivoted on said frame.
3. A combination collar clasp of the character described, said collar clasp comprising a frame, collar tab engaging means on said frame including a stationary member and a relatively movable member, tie clasping means on said frame including a movable arm, and operating connection means between the movable member of said collar tab engaging means, and said movable arm of said tie clasping means, said operating connection means effecting closing and locking and unlocking and opening of said movable member of said collar tab engaging means as said movable arm of the tie clasp means is manually manipulated into closed and open positions, respectively.
4. A combined collar clasp and necktie holder comprising a frame, collar tab engaging means on said frame comprising a relatively rigidly connected member and a pivoted member for engaging opposite sides of the collar tab, tie clasping means on said frame comprising elements

arranged to encircle the necktie when in closed position, said elements being pivoted on said frame, said elements having cam portions engageable with the corresponding pivoted members to swing said pivoted members toward said rigidly connected members when said elements are pivoted from their open positions toward their closed positions.

5. A combined collar clasp and necktie holder comprising a frame, collar tab engaging means on said frame comprising a relatively rigidly connected member and a pivoted member for engaging opposite sides of the collar tab, tie clasping means on said frame comprising elements arranged to encircle the necktie when in closed position, said elements being pivoted on said frame, said elements having cam portions engageable with the corresponding pivoted members to swing said pivoted members toward said rigidly connected members when said elements are pivoted from their open positions toward their closed position, said cam portions having a part engageable with the corresponding pivoted members while said pivoted members and said elements are in their closed positions for locking said pivoted members and said elements in their closed positions.

6. A combined collar clasp and necktie holder comprising a frame having oppositely projecting relatively rigid integral arms thereon arranged to engage behind the tabs of the collar, oppositely projecting swingable arms pivoted on said frame for engaging the front of the collar tabs in opposition to said rigid integral arms, tie clasping means mounted on said frame and including opposed elements pivoted on said frame and arranged to encircle the tie when in closed position, said opposed elements being formed with cams engageable with said swingable arms when said opposed elements are swung from open to closed position so as to clamp said swingable arms against the front of the collar tabs.

7. A combined collar clasp and necktie holder comprising a frame having oppositely projecting relatively rigid integral arms thereon arranged to engage behind the tabs of the collar, oppositely projecting swingable arms pivoted on said frame for engaging the front of the collar tabs in opposition to said rigid integral arms, tie clasping means mounted on said frame and including opposed elements pivoted on said frame and arranged to encircle the tie when in closed position, said opposed elements being formed with cams engageable with said swingable arms when said opposed elements are swung from open to closed position so as to clamp said swingable arms against the front of the collar tabs, said opposed elements being hook-shaped and having terminal portions arranged to overlap while said opposed elements are in the closed position.

8. A combined collar clasp and necktie holder comprising a frame having oppositely projecting relatively rigid integral arms thereon arranged to engage behind the tabs of the collar, oppositely projecting swingable arms pivoted on said frame for engaging the front of the collar tabs in opposition to said rigid integral arms, tie clasping means mounted on said frame and including opposed elements pivoted on said frame and arranged to encircle the tie when in closed position, said opposed elements being formed with cams engageable with said swingable arms when said opposed elements are swung from open to closed position so as to clamp said swingable arms against the front of the collar tabs, said op-

posed elements being hook-shaped and having terminal portions arranged to overlap while said opposed elements are in the closed position, said terminal portions being oppositely sprung so as to engage frictionally in their overlapped closed position.

9. A combined collar clasp and necktie holder comprising a frame having oppositely projecting relatively rigid integral arms thereon arranged to engage behind the tabs of the collar, oppositely projecting swingable arms pivoted on said frame for engaging the front of the collar tabs in opposition to said rigid integral arms, tie clasping means mounted on said frame and including opposed elements pivoted on said frame and arranged to encircle the tie when in closed position, said opposed elements being formed with cams engageable with said swingable arms when said opposed elements are swung from open to closed position so as to clamp said swingable arms against the front of the collar tabs, said frame being U-shaped in cross section and U-shaped in plan, said relatively rigid integral arms projecting laterally outwardly from the ends of the bight

of said frame in longitudinal alignment with said bight.

10. A combined collar clasp and necktie holder comprising a frame having oppositely projecting relatively rigid integral arms thereon arranged to engage behind the tabs of the collar, oppositely projecting swingable arms pivoted on said frame for engaging the front of the collar tabs in opposition to said rigid integral arms, tie clasping means mounted on said frame and including 10 opposed elements pivoted on said frame and arranged to encircle the tie when in closed position, said opposed elements being formed with cams engageable with said swingable arms when said opposed elements are swung from open to 15 closed position so as to clamp said swingable arms against the front of the collar tabs, said frame being U-shaped in cross section and U-shaped in plan, said swingable arms having their inner ends pivoted within the bight of said frame, and said 20 opposed elements being pivoted on the legs of said frame.
